UNITED STATES PATENT OFFICE.

PERRY C. SMITH, OF INDIANAPOLIS, INDIANA.

DESIGN FOR A CREAM-SEPARATOR.

SPECIFICATION forming part of Design No. 34,727, dated July 2, 1901.

Application filed May 16, 1901. Serial No. 60,618. Term of patent 7 years.

To all whom it may concern:

Be it known that I, PERRY C. SMITH, a citizen of the United States, residing at Indianapolis, in the county of Marion and State of Indiana, have invented and produced a new and original Design for Cream-Separators; and I do declare the following to be a full, clear, and exact description of the same, reference being had to the accompanying drawings, forming a part thereof.

My invention relates to vessels in which cream may be separated from milk; and the purpose of the invention is to provide a design for the bodies of vessels of this character that is both useful and ornamental.

Referring to the drawings, Figure 1 is a perspective view looking downwardly upon a vessel designed according to my invention, and Fig. 2 is a perspective view thereof looking upwardly from below the same.

Similar letters of reference in the two figures refer to like parts in the drawings.

The leading features reside in the general external contour of the body, including the bottom, of the vessel, in the arrangement of the sight-gages, and in the skirt-like base, having an aperture therein opposite the lower sight-gage, as illustrated in the drawings, in which the body A is circular in form, having a funnel-shaped bottom B, below which ex-

tends a skirt-like base C, which in external appearance appears to be a part of the vessel-body proper, A, being of the same diameter. At the front of the body A are narrow sight-gages D and E, extending vertically and arranged one below the other. Below the gage E is a similar gage F, attached to the bottom B of the vessel, the gages having, respectively, raised retaining-frames *a b d*. At the smaller end or bottom of the bottom B is a suitable stop-cock G, attached thereto, which, although a necessary operative attachment, is a subordinate feature of my design. In the base C is an aperture H opposite the gage F. The lower edge *h* of the base C is in a plane corresponding to the plane of the lower extremity of the bottom B. At the junction of the bottom B with the body A and the base C is an annular groove I in the exterior of the vessel.

What I claim as my invention, and desire to secure by Letters Patent, is—

The design for a cream-separator, substantially as herein shown and described.

In testimony whereof I affix my signature in presence of two witnesses.

PERRY C. SMITH.
